(No Model.)

J. P. MILLER.
BRICK MACHINE.

No. 451,714.

Patented May 5, 1891.

Fig. 1.

UNITED STATES PATENT OFFICE.

JOSEPH P. MILLER, OF HADDONFIELD, NEW JERSEY.

BRICK-MACHINE.

SPECIFICATION forming part of Letters Patent No. 451,714, dated May 5, 1891.

Application filed July 26, 1889. Renewed October 18, 1890. Serial No. 368,535. (No model.)

To all whom it may concern:

Be it known that I, JOSEPH P. MILLER, a citizen of the United States, residing at Haddonfield, in the county of Camden and State 5 of New Jersey, have invented a new and useful Improvement in Brick-Presses, which improvement is fully set forth in the following specification and accompanying drawings.

My invention relates to improvements in 10 brick-presses; and it consists of novel gearing for operating the plunger, adapted to be adjusted to take up wear.

The invention further consists of an improved construction of the side arms of a 15 clamping-bar and the bearing-boxes therefor.

The invention further consists of the construction and arrangement hereinafter more fully set forth and claimed.

Figure 1 represents a perspective view of a 20 brick-press, partly broken away, embodying my invention. Figs. 2, 3, 4, 5, 6, 7, and 8 represent views of detached parts thereof on enlarged scales.

Similar letters and numerals of reference 25 indicate corresponding parts in the several figures.

Referring to the drawings, A designates a frame having a plunger B, and C designates a compressing chamber or mold, which features are well known in the art.

A lever D is pivotally mounted on the frame and constructed with a heel E, having trunnions F extending through the sides of the said frame, and provided with removable 35 steel bushings G, which are affixed thereto by screws 1. The heel E of said lever is also formed with a slot 2 and ears 3 to receive a wheel H, adapted to bear against the lower end of the plunger B. A curved sectional 40 gear-head J is fitted close over the free end of the lever D, and has an arm J', formed with openings K for the passage therethrough of set-screws L, and bears on the top surface of the said lever. The openings K are elongated and larger than the screws L to permit 45 of a longitudinal adjustment of the head J.

The lever D has a lug M in rear of the arm J' of the head J, in which is located an adjusting-screw N, adapted to bear against the rear 50 edge of said arm J' and force the same outward when adjusted.

A shaft P is mounted in suitable bearings in the frame at a desirable elevation and constructed with a lug 4 to engage a stop 5. A sectional gear Q is attached to the shaft and 55 meshes with the teeth of the head J. To the one end of the said shaft is secured a crank-rod R, by which the parts are operated.

The bar or head S of the mold or chamber C is formed with tapered openings 6 to receive the arms T, whose upper ends are screw-threaded and also tapered, as at 7, to fit in openings 6. By this means a nut to support the bottom of bar on the tapered ends of the arms is dispensed with and a strong and solid 60 connection between the parts is obtained. A set-nut 8 is mounted on the end of each of the arms and bears on the bar S, and over the said set-nut is situated a jam-nut 9. By this construction the arms T are strengthened, and 65 thereby made to resist wear and breakage. The lower ends of the arms T are adjustably connected to the heads 10 of the journal plates or yokes U. Said lower ends of the arms are formed with upper and lower screw-threads 70 11 and 12, intersected by a plain surface 13, which passes through an opening in the head 10 of each plate or yoke U. The upper screw-threads 11 are adapted to receive jam-nuts 14, which bear against the tops of said heads 80 10, and the lower screw-threads 12 have adjusting or set nuts 15 mounted thereon, and are accessible for manipulation by means of a slot 16, formed in the heads, and by this means the said arms are made adjustable. 85 The lower parts of the plates or yokes U are constructed with slots whose bottom wall have an integral feather or spline 18.

Two half-boxes V, with grooved sides 19 and semicircular faces 20, are removably located in the openings 17, and the grooves of the lower half-boxes fit over the feathers or splines 18. These boxes surround the steel bushings G on the trunnions F of the heel E of the lever D, and the capped ends 21 of said 95 trunnions bear on the outer surfaces of the boxes, as shown in Fig. 1. When the trunnions, with their bushings G, are in position in the lower half-boxes, the upper half-box is inserted in opening 17 over the bushings and 100 held in adjustable connection therewith by a tapered key W, passing through an open-

ing 22 in the plates or yokes U, and which engage the top grooves in the said upper half-boxes, as shown in Figs. 1, 2, 3, and 4.

To operate the machine shown in Fig. 1, 5 the crank-rod R is raised to give a semi-rotation to gear Q, which will lower lever D and force the plunger B upward to compress the brick. The reverse movement of the rod R will allow the plunger to descend. The 10 lower end of the plunger has continuous bearing on the wheel H, and friction and wear are thereby reduced. To limit the rotation of the shaft P, the lug 4 thereof bears on the stop 5, and thereby a disengagement of the gear Q 15 and teeth of the head J is prevented.

As shown in Fig. 6, the construction of the head J is slightly modified. In this instance the teeth are formed in a concave line and engage the gear Q. When this construction 20 is employed, the rod R is pressed downwardly to elevate the plunger. The shaft P may be located at any elevation desired; but when the construction shown in Fig. 6 is employed it will be situated lower than as shown in 25 Fig. 1.

The improvements set forth, consisting of the bar S, with tapered holes to receive tapered ends of the arms T, having a lower plate or yoke with removable boxes held over 30 a steel bushing, and the gearing as set forth, strengthen the machine in order to resist wear and provide for a more direct expenditure of the power applied to the bar R.

Having thus described my invention, what 35 I claim as new, and desire to secure by Letters Patent, is—

1. In a brick-press, compressing mechanism, combined with a lever having an adjustable sectional gear, a shaft having a lug to 40 engage a stop, a sectional gear on said shaft adapted to mesh with the aforesaid gear, and means for operating said shaft, substantially as described.

2. In a brick-press, the compressing mechanism, a bar having tapered holes in each 45 end, side arms fitting in said bar, having tapered ends, and journal plates or yokes adjustably connected to the arms, all combined and arranged substantially as described.

50 3. In a brick-press, the compressing mechanism, combined with a bar having tapered holes in the ends thereof, side arms having the upper ends thereof tapered and mounted in the tapered holes of said bar, journal plates 55 or yokes attached to the lower ends of said

arms, and half-boxes removably mounted in said plates or yokes, substantially as described.

4. In a brick-press, the compressing mechanism comprising a plunger and chamber, a lever having a heel formed with trunnions, 60 compressing-bars, side arms attached to said bars at their upper ends, journal plates or yokes adjustably secured to the lower ends of said bars, having slots therein whose walls are constructed with a feather or spline, 65 grooved half-boxes removably mounted in said slot of the plates, and tapered key for holding said boxes intact with said plate, substantially as described.

5. In a brick-press, arms attached to a bar 70 which engages the compressing-chamber, combined with journal-plates connected to the lower ends of said arms and having sectional journal-boxes removably held therein, substantially as described. 75

6. In a brick-machine, the arms T, supporting a bar S, combined with journal-plates adjustably connected to the lower ends of said arms and adapted to hold said journal-boxes, substantially as described. 80

7. The plates or yokes U, carried by arms and having openings therein whose walls are formed with feathers or splines, half-boxes with grooves, and a tapered key, all combined and arranged substantially as described. 85

8. In a brick-press, a frame with a mold thereon, said mold having a head with tapering holes or openings therein, a plunger, an oscillating lever adapted to operate said plunger and having its journal-bearings in 90 boxes fitted in a yoke, arms adjustably fitted to said yoke and having tapering upper portions and threaded ends, said tapering portions being adapted to fit in the tapering openings in the said bar, and nuts on said 95 threaded ends, said parts being combined substantially as described.

9. In a brick-press, a lever with a lug thereon, in combination with the sectional gear J, having the arm J', the latter having the enlarged openings K, the screws L in said openings, and the screw N, passing through said lug of the lever and bearing against the arm J', substantially as and for the purpose set forth. 100

JOSEPH P. MILLER.
